ADJUSTABLE AND INTERCHANGEABLE ADVERTISING SIGN

Filed July 9, 1927

Inventor:
August Kugler
5 Frankfurt
Germany

UNITED STATES PATENT OFFICE.

AUGUST KUGLER, OF STUTTGART, GERMANY.

ADJUSTABLE AND INTERCHANGEABLE ADVERTISING SIGN.

Application filed July 9, 1927. Serial No. 204,613.

The fixation of advertising signs between two poles has been carried out hitherto by making in the poles, near the top end of the same and prior to the erection, holes designed to receive the bolts which carry the cross-beams which extend from one pole to the other and support the characters. The characters themselves were fixed on the cross-beams in a similar manner.

10 This fixation presents the inconvenience that, after the erection of the poles, the holes for the reception of the bolts for the cross-beams were not at accurately the same distance from the ground, so that fresh holes had to be bored either in one or in both poles in order to make the cross-beams parallel with the ground.

It is further rather difficult to mount the characters in vertical position on the cross-beams when the holes were bored beforehand for the reason that, when the cross-beams have been fixed on the poles, they bend sometimes.

This invention has for its object to avoid said inconveniences by making the cross-beams, and thereby the rows of characters and the several characters themselves adjustable in the longitudinal and transverse direction with regard to the poles and to make the characters themselves adjustable in the direction of the cross-beams. The adjustability of the cross-beams with regard to the poles is obtained by mounting one cross-beam in an eye, which is securely fixed on one of the poles by a clip, an extension arm of the eye being clamped by the clip. The characters are adjustably mounted on the cross-beams in a similar manner.

The improved fixation, according to the invention, presents further the advantage that the characters are interchangeable and that the cross-beams might be curved from the one pole to the other.

An embodiment of the invention is shown, by way of example, in the accompanying drawing in which:

Fig. 1 shows a fixation of a cross-beam to a pole,

Fig. 2 shows in which manner a bow-shaped cross-beam is fixed on a pole. 50

Fig. 3 illustrates the fixation of a character on a cross-beam.

Fig. 4 shows the connection of a cross-beam with a pole.

Fig. 5 is a diagrammatic view showing the 55 two posts.

Clips *b* are placed on the pole *a*, and under these clips metal straps *c* forming each an eye *d* at the top end are clamped. The eyes *d* serve each to hold one end of a 60 cross-beam *e*. On each cross-beam a number of eyes *f* of metal straps *g* are mounted, the lower end of each metal-strap being fixed by screws *h* to the characters *i*.

In order to avoid the poles sinking or 65 adopting an inclined position in the ground, the poles *a* are embedded each in a concrete foundation *Z* so that they cannot alter their positions.

I claim:—

1. Adjustable and interchangeable advertising signs, comprising in combination two poles, two cross-beams on which the characters are fixed, two clips on each pole placed a convenient distance apart, a metal strap 70 75 on each end of each cross-beam having an eye at the upper end and engaging the cross-beam and the lower end of each strap being clamped against the post by the corresponding clip.

2. In an adjustable and interchangeable advertising sign as specified in claim 1, in combination with the poles and the cross-beams, a number of metal straps forming each an eye at the top end mounted on each 80 85 cross-beam, characters fixed on the lower portion of said metal straps by screws, and a concrete foundation for each pole.

In testimony whereof I affix my signature.

AUGUST KUGLER.
